HIGH FREQUENCY TRANSMITTER

Frank Powell Best, London, England, assignor to
 Radio Corporation of America, a corporation of
 Delaware

Application February 25, 1933, Serial No. 658,621
 In Great Britain March 4, 1932

3 Claims. (Cl. 250—17)

This invention relates to radio and other high frequency transmitters and more particularly to high frequency telegraph transmitters of the so-called "absorber type" by which expression is meant transmitters of the type wherein the load upon the driving source of anode potential is maintained substantially constant during all conditions of keying by providing a tube in shunt across said source, said tube being controlled in accordance with the keying so that it places upon said source a load of such magnitude that the total load thereon (which is made up of the load due to the absorber tube and that due to the signalling tube or tubes) is constant during keying.

The invention has for its object to provide an absorber type transmitter which shall be simple and cheap to construct, easy to control, simple as regards keying arrangements and capable of utilizing alternating current of a frequency usually available (e. g. 500 cycles or 50 cycles single phase or multiphase) for keying. Further objects are to provide a transmitter in which all the parts except of course the key itself (or keying relay if any) shall be static, i. e. shall not involve the use of mechanically moving parts, and wherein "key-clicks" shall be entirely eliminated or substantially reduced.

According to this invention keying is accomplished in a transmitter of the kind in question by controlling the alternating current supply to a rectifier unit whose rectified output is utilized to provide bias potentials to the absorber tube or tubes and to the oscillating tube or tubes the arrangement being such that the total load upon the source of anode potential is substantially the same for both positions of the keying means.

The invention is illustrated in the diagrammatic drawing accompanying the provisional specification which drawing shows one arrangement in accordance with the invention. Referring to the said drawing, 1 is a high frequency oscillating tube whose output is coupled to a transmitting aerial as shown. The anode potential for said tube is supplied between the terminals HT+ and HT- and in shunt across these terminals is connected the anode-cathode space of an absorber tube 2 having the usual resistance 3 in its anode circuit. Controlling bias for the tubes 1, 2 is obtained from tappings on a potentiometer resistance 10 which is shunted by a condenser 11, said potentiometer resistance being connected to receive the rectified output from a full wave rectifier which in the example illustrated comprises a pair of diodes 4, 5. Obviously,

however, any other suitable rectifier arrangement may be employed e. g. a rectifier having a metallic envelope which acts as an electrode may replace the diodes. Alternating current is fed to the diodes or other rectifier arrangement through a transformer 7 and a variable resistance 8 in series with said transformer 7 serves to adjust the potential applied to the primary of said transformer. Of course, additional direct current bias may be applied to the grid of any of the tubes (e. g. the tube 2) by means of a battery or other suitable means where such added bias is necessary for correct operation. In series with the primary of said transformer 7 and resistance 8 is a key 9 the keying circuit being energized from an available alternating current source which is indicated by the letters AC and may be of the customary 800 cycle frequency commonly available for shipboard and similar transmitters. The alternating current source also supplies filament heating current for the various tubes as shown via transformers, the transformer 6 serving to energize the filaments of the diodes 4 and 5. Of course where a suitable direct current supply is available the two tubes 1, 2 may have their filaments energized by direct current instead of, as shown, by alternating current.

The circles shown in the drawing indicate the usual measuring instruments for observing the performance of the arrangement as a whole. When the key 9 is closed a voltage drop will be set up across the resistance 10 a point on which is, as will be seen, earthed. As a result, when the key is closed the grid of the tube 2 receives positive potential and the grid of the tube 1 negative potential so that in these circumstances the tube 2 passes current and applies a predetermined load across the terminals HT+ and HT-, while the tube 1 is prevented from oscillating. The load applied by the valve 2 in these circumstances is made equal to the load applied across the same terminals by the tube 1 when the said tube is oscillating.

When the key 9 is open the grid of the tube 2 and the grid of the tube 1 are both connected to earth through the appropriate parts of the resistance 10 and if the tube 2 be of suitable characteristics no current will flow therethrough in these circumstances, while the tube 1 will generate high frequency oscillations. By adjusting the positions of the tapping points upon resistance 10 the total load upon the terminals HT+ and HT- may be maintained constant while keying. A further adjustment by means of the resistance 8 enables accurate control of the voltage set up.

- across the resistance 10 to be obtained and this makes the regulation of the current absorbed by the absorber tube very simple. The condenser 11 of course acts as a smoothing system and controls 5 the rate at which voltage is built up across the resistance 10. This condenser, which may if desired be replaced by a more complex smoothing system, should be adjusted to reduce key-clicks to a minimum.
- 10 In an actual embodiment the maximum voltage output from the rectifying system was about 1,000 volts and the current in the resistance 10 about 100 milli-amperes. The condenser 11 was about .25 microfarads capacity and the absorber tube 15 shown in the drawing as one tube consisted in fact of two tubes in parallel.
- It is found that by accurately adjusting the various components of the circuit it is possible practically to reduce key-clicks to such an extent 20 that it is possible to operate a short wave telegraph transmitter as shown in the accompanying drawing and a short wave telephone receiver simultaneously with negligible interference in the telephone channel from the telegraph 25 channel.
- Having now particularly described and ascertained the nature of my said invention and in what manner the same is to be performed, I declare that what I claim is:—
- 30 1. In combination a high frequency oscillatory tube, a source of anode potential for said tube, an absorber tube having its anode to cathode impedance connected in shunt with said source, a source of alternating current, a circuit for sup- 35 plying current from said alternating current source to a rectifier arrangement, a potentiometer resistance shunted by a smoothing unit connected to the output of said rectifier arrangement, a connection between a point on said potentiometer 40 and the control grid of the absorber tube, and a connection between a point on said potentiometer and the control grid of the high frequency oscil- latory tube.
- 45
2. Transmitting means comprising, a thermionic oscillation generator having control grid and anode electrodes connected in oscillation producing circuits, and a source of energizing potentials connected with the anode of said tube and means for keying the oscillations produced comprising, a thermionic rectifier having input electrodes connected by way of a switch to a source of undulatory energy and output electrodes connected by way of a potentiometer to the control grid of 80 said oscillation generator in such a manner that when said key is in one position said oscillation generator is biased to cut-off and in the other position said oscillation generator is operative, and means for insuring a constant drain on said source of potentials connected with the anode of said oscillation generator including, an additional thermionic tube having its anode connected to the first named source of potentials and its control grid connected to a point on said potentiometer such that when said oscillation generator is biased to cut-off said additional tube is conductive, and vice versa. 85
3. Signalling means comprising, a thermionic relay tube having input and output circuits operative at carrier frequencies, said output circuits being energized by a source of direct current potentials, means for keying the oscillations in said tube comprising a thermionic rectifier having an input circuit connected by way of a switch to 100 a source of energizing energy and output electrodes connected by way of a resistance to the control grid of said tube, whereby the operativeness of said tube is determined by the open or closed position of said switch, and means for insuring a constant drain of energy on said direct current source comprising an additional thermionic tube having its anode to cathode impedance connected in parallel with said source and its control grid connected to a point on said re- 105 sistance. 110
